CLAIM

The ornamental design for a headband as shown and described.

DESCRIPTION

FIG. 1 is a top, front, left-side perspective view of a new and ornamental design for a headband.

FIG. 2 is a left-side elevation view of the headband shown in FIG. 1.

FIG. 3 is a right-side elevation view of the headband shown in FIG. 1.

FIG. 4 is a front elevation view of the headband shown in FIG. 1.

FIG. 5 is a rear elevation view of the headband shown in FIG. 1.

FIG. 6 is a top plan view of the headband shown in FIG. 1.

FIG. 7 is a bottom plan view of the headband shown in FIG. 1; and,

FIG. 8 is a bottom, rear, right-side perspective view of the headband shown in FIG. 1.

The wireframe lines shown in the figures are intended to depict surface contour and are not intended to be surface ornamentation.

1 Claim, 8 Drawing Sheets
